(57) **CLAIM**

The ornamental design for a fishing tackle caddy, as shown and described.

DESCRIPTION

FIG. 1 is a top view of a fishing tackle caddy showing a new design;

FIG. 2 is a bottom view thereof;

FIG. 3 is a front view thereof;

FIG. 4 is a back view thereof;

FIG. 5 is a left side view thereof;

FIG. 6 is a right side view thereof;

FIG. 7 is a front isometric view thereof; and,

FIG. 8 is a back isometric view thereof.

The broken lines in the drawing represent portions of the article that form no part of the claimed design.

1 Claim, 8 Drawing Sheets
